(57) **CLAIM**

The ornamental design for a housing for electric and electronic components, as shown and described.

DESCRIPTION

FIG. 1 is a perspective view of a first embodiment of a housing for electric and electronic components showing our new design;

FIG. 2 is a front elevational view of the housing for electric and electronic components of FIG. 1;

FIG. 3 is a rear elevational view of the housing for electric and electronic components of FIG. 1;

FIG. 4 is a left side elevational view of the housing for electric and electronic components of FIG. 1;

FIG. 5 is a right side elevational view of the housing for electric and electronic components of FIG. 1;

FIG. 6 is a top plan view of the housing for electric and electronic components of FIG. 1; and

FIG. 7 is a bottom plan view of the housing for electric and electronic components of FIG. 1.

FIG. 8 is a perspective view of a second embodiment of a housing for electric and electronic components showing our new design;

FIG. 9 is a front elevational view of the housing for electric and electronic components of FIG. 8;

FIG. 10 is a rear elevational view of the housing for electric and electronic components of FIG. 8;

FIG. 11 is a right side elevational view of the housing for electric and electronic components of FIG. 8;

FIG. 12 is a left side elevational view of the housing for electric and electronic components of FIG. 8;

FIG. 13 is a top plan view of the housing for electric and electronic components of FIG. 8; and,

FIG. 14 is a bottom plan view of the housing for electric and electronic components of FIG. 8.

The broken lines shown in the drawings illustrate portions of the housing for electric and electronic components that form no part of the claimed design.
